US00D537428S

(12) **United States Design Patent** (10) **Patent No.:** **US D537,428 S**
Fahlgren (45) **Date of Patent:** **** Feb. 27, 2007**

(54) **HANDSET**

(75) Inventor: **Anton Fahlgren**, Tampere (FI)

(73) Assignee: **Nokia Corporation**, Espoo (FI)

(**) Term: **14 Years**

(21) Appl. No.: **29/229,143**

(22) Filed: **May 4, 2005**

(30) **Foreign Application Priority Data**

Nov. 4, 2004 (FI) M20040173

(51) **LOC (8) Cl.** **14-03**

(52) **U.S. Cl.** **D14/138**

(58) **Field of Classification Search** D14/191,

D14/138, 147-148, 247-248, 144, 496, 156,

D14/341-347; 379/433.01-433.13; 455/575.3,

455/566, 575.1, 556.1, 556.2, 90.3; D21/517;

D16/208

See application file for complete search history.
